UNITED STATES PATENT OFFICE.

CARL WEGENER, OF BERLIN, GERMANY.

SMOKELESS-COMBUSTION FURNACE.

SPECIFICATION forming part of Letters Patent No. 712,467, dated October 28, 1902.

Original application filed October 17, 1900, Serial No. 33,389. Divided and this application filed December 3, 1901. Serial No. 84,592. (No model.)

To all whom it may concern:

Be it known that I, CARL WEGENER, a subject of the King of Prussia, German Emperor, residing at No. 14 Gitschinerstrasse, Berlin, 5 Prussia, German Empire, have invented new and useful Improvements in and in Connection with Smokeless-Combustion Furnaces, of which the following is a specification.

The present invention relates to improvements in and connected with that class of furnaces in which the fuel is fed from underneath below an upper layer of burning fuel. By the introduction of fresh fuel underneath the already-burning layer the introduced 15 layer receives a preliminary heating from above, and the heating-gases are generated by perfectly smokeless combustion, whereby the products of distillation are completely oxidized as they pass through the burning 20 layer.

This invention has for its object to obtain a better combustion and a more perfect utilization or heating effect of the fuel by a more suitable general arrangement of the furnace, 25 and, further, by improved means of introducing the air of combustion to the different zones of the burning fuel.

The accompanying drawing shows in vertical section one form of construction in which 30 my invention may be carried into effect.

As shown in the drawing, the combustion-chamber 1, into which the fresh fuel is fed through the pipe 6 by means of piston 12, is surrounded by a pipe 39, coiled in such manner 35 that the top coil is narrower than the bottom one, this coiled pipe being itself surrounded by a mantle or casing 40. The pipe 39 is connected by pipes 41 and 42 to a water-tank or to a steam-boiler, so that it is protected against burning by the cooling action 40 of the water. The sole of the combustion-chamber is formed as a movable disk grate 38, the air being admitted under pressure to the combustion-chamber by an air-passage 45 and the space between contiguous coils of the pipe 39 and by an air-supply 44. The pipe is provided with a nozzle consisting of openings arranged step-like over one another, so as to distribute the air in every direction, and 50 thus insure its intimate mixing with the ascending gases.

The walls of the flue 2 for drawing off the combustion-gases may be provided with open-

ings 52 for the introduction of fresh air, whereby the carbon monoxid evolved is transformed into carbon dioxide. 55

This application is a division of my application filed October 17, 1900, Serial No. 33,389.

What I claim, and desire to secure by Letters Patent of the United States, is— 60

1. In a smokeless-combustion furnace in which the fresh fuel is fed from underneath below the layer of live fuel, the combination with the combustion-chamber, of a pipe for introducing fuel into said chamber, a flue for drawing off the combustion-gases, means for forcing the fuel through said pipe, and an air-conduit for supplying air to the furnace, the combustion-chamber being formed by a coiled pipe with spaces between the coils for admission of air to the burning fuel, substantially as and for the purpose stated. 70

2. In a smokeless-combustion furnace in which the fresh fuel is fed from underneath below the layer of live fuel, the combination 75 with the combustion-chamber formed by a coiled pipe with spaces between the coils, of a pipe for introducing the fuel into the said chamber, a flue for drawing off the combustion-gases, a piston for forcing the fuel through the said pipe, an air-conduit for supplying air into the space between the coiled pipe and the walls of the furnace, and an air-supply pipe for introducing air into the live fuel, substantially as and for the purpose stated. 85

3. In a smokeless-combustion furnace in which the fresh fuel is fed from underneath below the layer of live fuel, the combination with the combustion-chamber formed by a coiled pipe with spaces between the coils, of 90 a pipe for introducing the fuel into the said chamber, a flue for drawing off the combustion-gases, a piston for forcing the fuel through said pipe, an air-conduit for supplying air into the space between the coiled pipe and the walls of the furnace, and an air-supply pipe provided with a nozzle consisting of openings arranged step-like over one another, substantially as and for the purpose stated. 95

In witness whereof I have hereunto signed my name, this 21st day of October, 1901, in the presence of two subscribing witnesses.

CARL WEGENER.

Witnesses:

HEINRICH SPRINGMANN,
HANS PLOTZ.
